UNITED STATES PATENT OFFICE.

ISAAC ROSENHAFT AND ISRAEL HERSKOWITZ, OF NEW YORK, N. Y.

VANITY CASE.

Application filed March 16, 1922. Serial No. 544,230.

To all whom it may concern:

Be it known that we, ISAAC ROSENHAFT and ISRAEL HERSKOWITZ, subjects of the King of Rumania, residing at New York, county of New York, and State of New York, have invented certain new and useful Improvements in Vanity Cases, of which the following is a specification.

The objects of our invention are to provide a simple and compact vanity case adapted to hold a plurality of cosmetics including perfume.

Our vanity case is so constructed that it can be used to spray perfume upon the user, and it has compartments for holding a lip stick, eye-brow pencil and powder puff. It resembles in general appearance a watch case. The perfume is carried in the interior where the works of a watch would usually be, and between the hinged lid and the face is provided a space for holding a powder puff. Tubes closed on their inside ends, project into the interior of the case and are adapted to hold snugly a lip stick, eye-brow pencil or other form of solid cosmetic.

We attain these objects by the construction illustrated in the accompanying drawing.

Figure 1 is a longitudinal section of the vanity case. Figure 2 is a cross-section. Figure 3 is a perspective view of the case with the lid closed. Figures 4 and 5 show alternative methods of closing the perfume aperture.

The perfume 1 is held in chamber 2. Projecting upward from the casing of chamber 2 is a standard 3 which has a tapped hole through its center. A tube 4 projects within chamber 2. Tube 4 carries near its upper end a threaded sleeve 5 which fits over the tube and is soldered to it. The upper end of tube 4 is soldered into nozzle 6. Projecting into chamber 2 are tubes 7 and 8 which are closed at their lower ends and open at their tops. Lip stick 9 which is of a well-known form is encased in its slotted metallic sleeve 10. Metallic lug 11 projects from a cap 21 over the top of lip stick 9 and is for the purpose of pushing out the lip stick from sleeve 10 as it becomes used up. Sleeve 10 fits snugly into tube 7 with its head projecting out of the tube. In a similar manner eye-brow pencil 12 with its sleeve 13 fits into tube 8. Of course it is to be understood that other forms of holders of cosmetics can be used and held in tubes 7 and 8. Split ring

15 which is revolvably held in sockets formed in standard 3 is adapted to fit tightly over the end of nozzle 6 so as to close its aperture when not in use. Hinged to the casing of chamber 2 is a concave lid 14, which with a mating concavity in the adjacent wall of the casing of chamber 2 forms a chamber 16 which is adapted to hold a removable powder puff (not shown) or other 65 toilet article.

In order to use the case for spraying with perfume, ring 15 is turned back from over the aperture of nozzle 6 and the case is then grasped between the fingers. By pressing 70 against the more or less flexible casing of chamber 2 with lid 14 open or closed, much in the manner as an oil can is used, perfume 1 is forced up through the bottom of tube 4 and out through nozzle 6. The cosmetic 75 pencils 9 and 12 can be removed from their respective tubes 7 and 8 and applied to the face after which they can be returned being held in place by friction.

Instead of closing the aperture of nozzle 6 by ring 15, the methods shown in Figures 4 and 5 could be used. In Figure 4 disc 17 is shown revolvably fastened to nozzle 6 by pin 18. The aperture can be closed by turning disc 17 so as to cover it. In Figure 5, 85 nozzle 6 is shown with a slot formed in its head. Adapted to slide in this slot is a leaf 19. By pushing leaf 19 inward the aperture in nozzle 6 can be closed.

In order to permit the filling of chamber 90 2 with perfume, nozzle 6, which is attached to tube 4 carrying threaded sleeve 5, is turned sufficiently to unscrew sleeve 5 from standard 3.

We claim:

1. A vanity case comprising a chamber, for holding perfume, having a flexible wall for ejecting the perfume, another chamber having a hinged lid and a plurality of tubes 100 closed at their inner ends projecting within said first chamber for holding other cosmetics.

2. A vanity case comprising a chamber, for holding perfume, having a flexible wall for ejecting the perfume, a nozzle adapted 105 to be fastened to said chamber, and a split ring mounted to rotate about its ends for closing the aperture of said nozzle.

3. A vanity case comprising a chamber, for holding perfume, having a flexible wall for ejecting the perfume, a nozzle attached 110 to said chamber and a plurality of tubes

closed at their inner ends projecting within said chamber for holding solid cosmetics.

4. A vanity case comprising a chamber, for holding perfume, having a flexible wall 5 for ejecting the perfume and having projecting from it a standard with a hole in it, a nozzle adapted to be fastened to said standard and a split ring having its ends fitting into sockets formed in said standard, said 10 ring adapted to be rotated so as to tightly close the aperture of said nozzle.

5. A vanity case comprising a liquid container, a plurality of cosmetic containers inset within said liquid container and sealed therefrom, and means for dispensing liquid 15 from said container.

6. The combination with a perfume container of a recess formed in the side thereof, for the purpose of holding a powder-puff.

ISAAC ROSENHAFT.
ISRAEL HERSKOWITZ.
